UNITED STATES PATENT OFFICE

94,914

DESIGN FOR A SAUCER

Belle Kogan, New York, N. Y., assignor to Ebeling & Reuss, Inc., Philadelphia, Pa., a corporation of Delaware

Application January 3, 1935, Serial No. 54,703

Term of patent 7 years

To all whom it may concern:

Be it known that I, Belle Kogan, a citizen of the United States, residing at New York, in the county of New York and State of New York, have invented a new, original, and ornamental Design for a Saucer, of which the following is a specification, reference being had to the accompanying drawing, forming part thereof.

Fig. 2 is an edge elevational view thereof.

I claim:

The ornamental design for a saucer as shown. In testimony whereof, I have hereunto signed my name.

BELLE KOGAN.
